ANHYDROUS AMMONIA CONTROL OR SIMILAR ARTICLE

Theodore A. St. Clair, South Euclid, Ohio

Application January 14, 1953, Serial No. 23,126

Term of patent 3½ years
(Cl. D78—1)

To all whom it may concern:

Be it known that I, Theodore A. St. Clair, a citizen of the United States, residing at South Euclid, Ohio, have invented a new, original, and ornamental Design for an Anhydrous Ammonia Control or Similar Article, of which the following is a specification, reference being made to the accompanying drawings, forming a part hereof.

In the drawings,

Fig. 1 is a plan view of an anhydrous ammonia control showing my new design;

Fig. 2 is a front elevation thereof;

Fig. 3 is an elevation taken from the right of Fig. 1;

Fig. 4 is an elevation taken from the left of Fig. 1; and,

Fig. 5 is a rear elevation view thereof.

I claim:

The ornamental design for an anhydrous ammonia control or similar article, as shown.

THEODORE A. ST. CLAIR.
